UNITED STATES PATENT OFFICE.

FRANCIS J. ROMADKA, OF MILWAUKEE, WISCONSIN.

DESIGN FOR A MOTORCYCLE-TRUNK.

60,108.

Specification for Design.

Patented Dec. 27, 1921.

Application filed April 30, 1918. Serial No. 231,761. Term of patent 3½ years.

To all whom it may concern:

Be it known that I, FRANCIS J. ROMADKA, a citizen of the United States, residing at Milwaukee, in the county of Milwaukee and State of Wisconsin, have invented a new, original, and ornamental Design for Motorcycle-Trunks, of which the following is a specification, reference being had to the accompanying drawing, forming part thereof.

The figure is a perspective view of a motorcycle trunk, showing my new design.

I claim:

The ornamental design for a motorcycle trunk, as shown.

FRANCIS J. ROMADKA.
